UNITED STATES PATENT OFFICE

107,215

DESIGN FOR A VENDING MACHINE

David S. Bond, Brookline, Mass.

Application June 16, 1936, Serial No. 63,321

Term of patent 7 years

To all whom it may concern:

Be it known that I, David S. Bond, a citizen of the United States, residing at 66 Chiswick Road, Brookline, in the county of Norfolk and State of Massachusetts, have invented a new, original, and ornamental Design for Vending Machines, of which the following is a specification, reference being had to the drawing, forming part thereof. The figure is a perspective view of the vending machine showing my new design. The essential features of the design consist in

the arrangement of the panelling of the windows at the front with the corrugated effect at the top of the window elements.

The rear and sides of the device are plain without any surface ornamentations, the specific features of the design being associated with the front and top irrespective to the back, bottom and sides.

I claim:—

The ornamental design for a vending machine substantially as shown and described.

DAVID S. BOND.
